UNITED STATES PATENT OFFICE

161,413

DINER OR SIMILAR ARTICLE

Allen M. Berryhill, Charlotte, N. C., assignor to Do-Nut Dinette, Incorporated, Charlotte, N. C., a corporation of North Carolina

Application December 27, 1948, Serial No. 150,379

Term of patent 14 years

(Cl. D13—1)

To all whom it may concern:

Be it known that I, Allen M. Berryhill, a citizen of the United States, residing at Charlotte, in the county of Mecklenburg and State of North Carolina, have invented a new, original, and ornamental Design for a Diner or Similar Article, of which the following is a specification, reference being had to the accompanying drawing, forming part thereof.

The dominant features of my design reside in the portions shown in full lines.

I claim:

The ornamental design for a diner or similar article, as shown and described.

ALLEN M. BERRYHILL.
